New York, N.Y. 10003

Filed July 9, 1971, Ser. No. 161,428

Term of patent 14 years

Int. Cl. D2—02

U.S. Cl. D2—28

FIG. 1 is a side perspective view of a pair of slacks showing my new design; and

FIG. 2 is a perspective view of the other side thereof, the back being conventional.

The characteristic feature of my design resides in a slit formed through the outer side of each leg all as shown on the drawing.

I claim:

The ornamental design for a pair of slacks or similar article, as shown and described.
